UNITED STATES PATENT OFFICE.

WILLIAM HAINES AND LEWIS BREITINGER, OF PHILADELPHIA, PA.

WINDING-INDICATOR FOR WATCHES AND CLOCKS.

SPECIFICATION forming part of Letters Patent No. 248,810, dated October 18, 1881.

Application filed February 19, 1881. (Model.)

To all whom it may concern:

Be it known that we, WILLIAM HAINES and LEWIS BREITINGER, both citizens of the United States, residing in the city and county of Philadelphia, and State of Pennsylvania, have invented a new and useful Improvement in Winding-Indicators for Watches and Clocks, which improvement is fully set forth in the following specification and accompanying drawings, in

10 which—

Figure 1 is a face view of a watch embodying our invention. Fig. 2 is a similar view with the dial removed. Fig. 3 is a view of a portion of the face opposite to Fig. 2. Fig. 4 is an enlarged view of a detached portion thereof. Fig. 5 is a section in line *y y*, Fig. 4. Fig. 6 is a side elevation of a portion, partly sectional in line *x x*, Fig. 5. Fig. 7 is a view of a portion in line *z z*, Fig. 2, enlarged.

20 Similar letters of reference indicate corresponding parts in the several figures.

Our invention consists of an attachment to a watch or clock for indicating the extent the same is wound or run down.

25 It also consists of the ratchet-wheel having a back action for preventing tight winding of a watch or clock.

Referring to the drawings, A represents a dial, A' a barrel, and A" the barrel-arbor—30 parts of a watch or clock generally of well-known form and construction—the invention being hereinafter described as applicable to watches.

To the arbor is rigidly secured a pinion, B, 35 which meshes with a spur-wheel, B', the latter having a hub, C, on which is fitted a plate or armature, D, one end of which is of the form of a split disk or clip, E, which embraces the hub C above the wheel B' with considerable 40 friction or power, but allows said wheel to rotate when the watch is being wound.

Mounted on the armature D are two spur-wheels, F F', which gear with each other, the wheel F' gearing with a spur-wheel, F'', which, 45 located above the clip E, is secured to an arbor, C', and free of said clip receives motion from the wheel B' by action of a friction-spring, C'', which is of dishing form, and is sprung into a notch or shoulder at the bottom of the arbor 50 C', the latter passing freely through the clip E and wheel B'.

Fitted on the arbor C' is a collar, a, carrying an index or pointer, G, which appears above the dial A, the latter having graduations or characters coinciding with the path of rotation 55 of the index or pointer, the graduations or characters indicating the condition of the watch, whether entirely or partially wound or run down.

H represents a pinion, which is rigidly connected to the post of a wheel, H', which is geared to the regular running-gear of the watch or clock, and mounted between the plates thereof, the pinion H being so disposed that the wheel F of the armature D gears with it.

J represents the ratchet, fitted loosely on the winding-post or barrel-arbor, and provided with a pin, J', which projects into a segmental slot, b, in a cap, K, which is fitted on the square portion of the arbor, so as to move with the 70 arbor.

The operation is as follows: In winding the watch the key is applied to the arbor and operated as usual. The pinion B rotates the wheel B', and, owing to the friction of the clip 75 E of the armature D on the hub of said wheel, rotary motion is imparted to the armature and the wheel F is moved clear of the wheel H, so that the running-gear is not affected, the motion of the armature being limited by a pin, 80 a', or spring a''. Simultaneously therewith the wheel F'' is rotated and the index or pointer G is moved in the direction toward "up" on the dial A. On the first motion of the arbor A" the cap rotates, and when the end of its 85 slot b reaches the pin J the ratchet is rotated with the arbor, and the winding begins; but as soon as the power of the key is let go in order to make a fresh hold thereon, the pressure of the spring of the pawl or click c exerted on 90 the ratchet causes a back action or motion of said ratchet, so that the pinion B, instead of holding the wheel B' and causing the wheel F of the armature to stand out from the pinion H, receives a slight return or reverse motion, 95 which being imparted to the wheel B', and consequently to the armature, occasions the return of the wheel F to the pinion H and the consequent re-engagement of the former with the latter. The winding is continued and the other 100 operations are repeated until the watch is wound, the index or pointer G appearing at

"up" on the dial. As the watch runs down the pinion H connected to the running-gear, as has been stated, moves the wheels F F', and consequently the wheel F'', without disturbing the wheel B', and as the index G is connected to the arbor C' of wheel F'', it is carried around toward "down" on the dial, and thus the wound and unwound condition of the watch is at all times exhibited on the watch-dial.

10 Should the watch be too tightly wound, the back action or backward motion of the ratchet heretofore stated also serves to relieve the strain on the mainspring, and thus the great force of the spring is prevented from injuring the time-keeping qualities of the watch.

15 A portion of the wheel F'' is untoothed, or one of the teeth closed, as at e, so that when said wheel has made its full rotation during the winding of the watch and said portion e reaches the wheel F' the wheel B' continues its rotation, but the wheel F'' is stopped, whereby the index does not pass beyond the characters "up," the stoppage of the wheel F'' being occasioned by the inability of the portion e to mesh with the teeth of the wheel F', the friction-spring C'' losing its power to move said wheel F''.

20 As a majority of the watches of to-day are made with stationary arbors, our improvement 25 is to affect them only.

Having thus described our invention, what we claim as new, and desire to secure by Letters Patent, is—

1. An index-carrying wheel, in combination

with the barrel-arbor or winding mechanism 35 and an armature or plate which is provided with one or more wheels, connecting said index-carrying wheel with the running-down gear, said plate or armature being made rotatable or movable, so as to disengage its wheels 40 from the running-gear, substantially as and for the purpose set forth.

2. The ratchet J, loosely fitted on the barrel-arbor and provided with a pin, J', in combination with a cap, K, which turns with said arbor and has a segmental slot to receive said pin, substantially as set forth.

3. The wheel B', wheel F'', and friction-spring C'', in combination with the armature D, connected to the hub of said wheel B' by 50 the clip or friction-joint E, the wheels F F', and the barrel-arbor and running-gear, substantially as and for the purpose set forth.

4. The index G, wheel F'', and wheel B', in combination with the armature D, connected to 55 said wheel B' by the friction-joint E, and provided with wheels F F', and the barrel-arbor and running-gear, substantially as and for the purpose set forth.

5. The index G, in combination with the 60 wheel B', the armature with wheels F F', and the wheel F'', with untoothed or closed portion e, substantially as and for the purpose set forth.

WILLIAM HAINES.
LEWIS BREITINGER.
